UNITED STATES PATENT OFFICE.

THOMAS P. SWEENEY, OF SACRAMENTO, CALIFORNIA.

AUTOMATIC PRESSURE-RETAINING VALVE FOR AIR-BRAKES.

SPECIFICATION forming part of Letters Patent No. 416,516, dated December 3, 1889.

Application filed December 8, 1888. Serial No. 293,010. (No model.)

To all whom it may concern:

Be it known that I, THOMAS P. SWEENEY, of Sacramento, Sacramento county, State of California, have invented an Improvement in 5 Automatic Pressure-Retaining Valves for Air-Brakes; and I hereby declare the following to be a full, clear, and exact description of the same.

My invention relates to improvements in 10 air-brakes; and it consists of what I term an "automatic pressure-retaining valve," which may be operated in connection with the reservoir of an automatic brake mechanism and with connecting-pipes of the same, so that in 15 running down heavy grades the brakes can remain applied while the reservoir is being replenished.

Referring to the accompanying drawings for a more complete explanation of my invention, Figure 1 is a side elevation showing my 20 device applied to an automatic brake mechanism. Fig. 2 is a vertical section through the valve and chamber.

In the employment of what is known as an 25 "automatic air-brake" an auxiliary reservoir is fixed upon each car, having a valve mechanism, which is called a "triple valve," through which air is admitted to the reservoir, and by which it is also admitted from the reservoir to the 30 brake-cylinder by the reduction of the pressure in the train-pipe; but when it is necessary to replenish the auxiliary reservoir it is necessary to temporarily cut off the communication between this reservoir and the brake- 35 cylinder, so that the latter is without pressure while the reservoir is being replenished, and the movement of the valves to connect the reservoir with the train-pipe allows the air to escape from the cylinder. When this occurs upon heavy downgrades, it is a dangerous 40 thing, because the train will gain such momentum in a very short distance that it will be almost impossible to handle it and again check it. My invention is designed to 45 overcome this difficulty; and it consists in the employment of what I term a "pressure-retaining valve," which regulates or prevents the escape of air from the brake-cylinder while the train-reservoir is being replen- 50 ished.

In the drawings, A is the train-pipe, through which the air passes in the direction shown by the arrows.

B is a "triple-valve mechanism," so called.

C is an auxiliary reservoir, and D is the 55 brake-cylinder. These portions of the apparatus being well shown in the patents already issued and in use upon what is known as the "Westinghouse system," I shall not further describe them in this place.

E is a supplemental cylinder in which is fitted a cylindrical valve F. This cylinder is placed in a vertical position and has an opening in its top and also in its bottom. The opening in the bottom of the cylinder is connected with the train-pipe A, so that the pressure from said pipe may act upon the bottom of the piston-valve F to raise it, the interior of the cylinder being enough longer than the valve to allow it a certain amount 65 of movement longitudinally within the cylinder. At the upper end of the supplemental cylinder is an extension forming a chamber E, which is connected by a pipe L with the auxiliary or car reservoir. A horizontal passage 70 J is made transversely across the valve F, and holes are made in opposite sides of the cylinder E, which holes correspond with the passage in the valve when the valve is at its lowest point; but when the valve is raised 75 its passage will be carried above the line of the holes in the sides of the cylinder and will thus cut off communication through them.

T is the discharge passage or opening in the triple-valve chamber, through which air 85 from the brake-cylinder is ordinarily allowed to escape by the movement of the triple valve, which allows the auxiliary reservoir to be recharged. Above the upper end of the cylinder E is an extension, forming a chamber E', 90 having within it a piston N, which is provided with a stem M', extending downward through the head or diaphragm which separates the chambers E and E'. This opening T, as ordinarily employed, allows the air to 95 escape from the brake-cylinder D when the triple valve is so moved as to make connection between the train-pipe A and the auxiliary reservoir C; but in the present case this escape-opening T is connected by a pipe a 100

directly with the side of the valve-chamber E and the transverse passage J through the valve F.

V is the pipe which connects the brake-cylinder with the triple-valve chamber, and through which, when the valves are in proper position, air passes from the reservoir C to the brake-cylinder D, so as to apply the brake. In the ordinary construction, when 5 the triple valve is moved so as to admit air from the train-pipe to the reservoir, it also allows air to escape from the brake-cylinder through the pipe V and the opening T.

The operation of the device will then be as 10 follows: Air is pumped into the reservoir upon the engine to a pressure, say, of one hundred pounds, and by means of the engineer's valve it is allowed to pass through the train-pipe A into the auxiliary reservoirs C, which are be-

15 beneath each car. The triple-valve mechanism, which is already in use, and is therefore not here described, is so arranged that when the pressure from the train-pipe A is admitted into the triple-valve chamber B it moves the 20 valves so as to open communication directly with the reservoir C, so that air may flow into this reservoir up to any desired pressure. This movement of the valve also opens communication between the brake-cylinder D and 25 the opening T, which is ordinarily an escape or discharge passage, but which in my invention communicates through the pipe a with the side of the cylinder E, as above described.

Now, when it is desired to apply the brake, 30 suppose the pressure in the reservoir C to stand at seventy pounds. By means of the engineer's valve the pressure in the train-pipe may be reduced to something less than the pressure in the reservoir. The triple 35 valve will then be moved so as to open communication between the reservoir C and the brake-cylinder D, and any required pressure may be admitted into the cylinder D. When running down grades the leakage and gradual 40 escape of the air will reduce the pressure in the auxiliary reservoir C until it is below what is necessary for the proper control of the train. It is then necessary to resupply the auxiliary reservoirs from the engine-reservoir 45 by means of the engineer's valve. Air is allowed to pass through the train-pipe A, and acting upon the valves in the chamber B communication is opened between the train-pipe and the reservoir C, and at the same 50 time communication is opened between the brake-cylinder D and the discharge-opening T.

As formerly arranged the air would be allowed to escape from the brake-cylinder, and the train would be temporarily out of 55 control of the brakes and would be liable to attain a dangerous speed. In my invention, however, the pressure in the train-pipe, acting through the pipe G upon the bottom of the valve F, forces this valve up until the 60 passage J in the valve is out of line with the pipe a and the openings in the sides of the valve-chamber E. The pressure in the brake- 65

cylinder is thus retained, because this valve cuts off the escape of the air through the hole T. When the pressure in the reservoir C is 70 such as to balance the pressure in the train-pipe A, it acts through the pipe L, which connects the upper cylinder E' with the reservoir C, and pressing upon the piston M forces it down, and through the stem M' the 75 valve F is also forced down until the passage J is in line with the pipe a, when air may be allowed to escape from the brake-cylinder D to any desired degree. By reducing the pressure in the train-pipe to less than that in the 80 reservoir C the valves in the chamber B will again be moved so as to admit air into the brake-cylinder D. The amount of pressure in the train-pipe and this cylinder is controlled by the engineer's valve in the well-known manner.

In order to insure the prompt movement of the valve or piston F as soon as the pressures in the auxiliary reservoir and the train-pipe are equalized, I have shown a light spring b, 90 so disposed in the upper part of the valve-chamber E as to press upon the top of the valve F.

I have shown the valve-chamber E at some distance from the main valve-chamber B, for 95 convenience in describing; but in practice it may be placed in close connection with the discharge-opening T, so as to make the whole compact.

The object of the device is to keep the brakes 100 applied while the train-reservoirs are being recharged without in any way disturbing the valve mechanism at present in use and by an exterior supplemental device.

I do not wish to limit myself to the specific 105 arrangement and construction of parts herein shown, as the same may be modified or changed without departing from the spirit of my invention.

Having thus described my invention, what I 110 claim as new, and desire to secure by Letters Patent, is—

1. The improvement in automatic air-brake mechanism, consisting of a cut-off valve connected with the triple-valve mechanism and 115 exterior thereto, said valve acting to close the escape-passage from the brake-cylinder by the increase of train-pipe pressure.

2. The combination, with the auxiliary reservoir, brake-cylinder, and intermediate triple-valve mechanism of an automatic air-brake, of a cylindrical valve-chamber having openings made in its opposite sides in line with each other, a piston fitted to move within said cylinder and having a hole made transversely 125 through it corresponding with the holes in the sides of the cylinder when said piston is at one end of its stroke, a pipe connecting this end of the cylinder with the train air-supply pipe, a second pipe connecting the opposite 130 end of the cylinder with the auxiliary reservoir, and a pipe connecting one of the openings in the side of the valve-cylinder with the escape-passage at the triple-valve chamber,

whereby said passage is closed by the upward movement of the piston within the supplemental cylinder, substantially as described.

3. A supplemental cylindrical valve-chamber having openings in the opposite sides, a vertically-moving piston fitted therein and having a transverse opening corresponding with the openings in the sides of the chamber, in combination with the brake-cylinder, auxiliary reservoir, train-pipe, and triple-valve mechanism connected therewith, a pipe connecting one of the openings in the side of the supplemental cylinder with the escape-passage of the triple-valve mechanism, a second pipe connecting the bottom of said cylinder with the train-pipe, and a pipe connecting the top of said cylinder with the auxiliary reservoir, substantially as described.

4. The automatic air-brake mechanism, consisting of the auxiliary reservoir, the brake-cylinder, and the valves, whereby the supply and discharge of air is effected, in combination with a supplemental cylinder, a piston reciprocating therein, pipes connecting the opposite ends of said cylinder with the train-pipe and auxiliary reservoir, a passage through said reciprocating piston, and corresponding openings in the side of the cylinder, one of which is connected with the auxiliary-reser-

voir valve mechanism, so that the movements 30 of the supplemental piston in its cylinder will close or open the passage and simultaneously close or open the discharge from the brake-cylinder, substantially as described.

5. The automatic air-brake mechanism, consisting of an auxiliary reservoir, the brake-cylinder, and the triple - valve mechanism whereby the supply and discharge of air is effected, a supplemental cylinder having a piston reciprocating therein and the opposite 40 ends of said cylinder connected with the train-pipe and auxiliary reservoir, a transverse opening through said piston, and corresponding openings in the sides of the supplemental cylinder, together with a supplemental piston 45 fitted in the upper part of the supplemental cylinder, having a stem extending downward and pressing upon the top of the main piston, and a spring surrounding said stem and acting upon the main piston, substantially as de- 50 scribed.

In witness whereof I have hereunto set my hand.

THOMAS P. SWEENEY.
